Attorney

UNITED STATES PATENT OFFICE.

PETER H. SAN SOUCI, OF CENTRAL FALLS, RHODE ISLAND.

MUSIC-LEAF TURNER.

Application filed August 18, 1922. Serial No. 582,783.

To all whom it may concern:

Be it known that PETER H. SAN SOUCI, a citizen of the United States of America, residing at Central Falls, in the county of 5 Providence and State of Rhode Island, has invented new and useful Improvements in Music-Leaf Turners, of which the following is a specification.

The object of the invention is to provide 10 a simple and efficient construction of music leaf turner applicable to various keyed instruments of the piano and organ type and also to music stands for orchestral use and the like whereby a plurality of leaves of 15 sheet music and particularly loose or intermediate leaves thereof may be successively turned and held in proper position for reading and against displacement through jarring, drafts, and the like; and with this object in view the invention consists in a construction and combination of parts of which a preferred embodiment is shown in the accompanying drawings, wherein:—

Figure 1 is a front view of a device embodying the invention showing a loose leaf musical composition in operative relation therewith and with one of the leaves turned or subsequent to the operation of the device.

Figure 2 is a detail view of one of the 30 turning arms and the adjacent portion of the spindle by which it is carried.

Figure 3 is a detail sectional view of the 35 means for holding the spindles with the turning arms in their normal positions and for successively releasing the same to permit of the turning of the leaves.

Figure 4 is a detail perspective view illustrating one of the triggers.

The apparatus embodies, in addition to 40 any suitable desk or support 10, which may be a music stand or instrument desk or a separate board applicable to either a stand or a desk, upon which in suitable upper and lower bearing brackets 12 and 13 are 45 mounted rocking spindles 14, any desired number of which may be employed, for carrying the leaf turning arms 15. These leaf turning arms which consist of relatively small gauge rods are provided with terminal 50 screw heads consisting of wire or like rods designed to extend vertically or parallel with the outer free edges of the music sheets indicated at 17, and at their inner ends said turning arms furthermore carry clamping 55 tongues 18 designed to engage the inner or

binder edges of the sheets so as to effectively hold said sheets from displacement by air drafts or otherwise from the desk during the performance of the composition.

At their lower ends the rocker spindles 60 are provided with actuating springs 19 tensioned to swing the turning arms from the right to the left in the direction of progressive performance of the composition and terminally the said spindles are extended 65 to form operating arms 20 which are terminally disposed in operative relation with triggers which serve to normally hold them in position to maintain the spindle operating arms with the turning arms at the 70 right. The triggers above referred to consist of flat springs 22 secured one above the other on the face of the desk 10 by means of fasteners 21, one terminal of each spring being laterally deflected and formed with 75 an eye 23 in which the extremity of its operating arm may engage. Pressure applied on the laterally deflected terminal in a direction away from the operating arm will serve to release the latter for actuation by 80 its attendant spring. When it is desired to turn a sheet of the music it is only necessary to actuate the trigger corresponding with the arm to be operated so as to release the latter and permit of the turning of the 85 spindle by means of its actuating spring, so that it may swing the turning arm from its original position at the right to a position at the left as shown in Figure 1. The actuation of these triggers obviously may 90 be effected by a momentary touch of the finger of the performer and therefore without withdrawing the hands for any protracted period from the keyboard or the instrument which is being manipulated and 95 hence without the loss of time which is ordinarily incident to the manual turning of the leaves of sheet music.

Having described the invention, what is claimed as new and useful is:—

1. A music leaf turner having in combination with a suitable desk a spring actuated rocker spindle carrying a radial turning arm, the lower extremity of said spindle being extended to form a lateral operating arm, and a movable trigger for normally holding the operating arm in opposition to the tension of the spindle actuating spring, said turning arm having a terminal cross head for extension parallel with the free 110

outer edge of a music sheet and provided adjacent to the spindle with a clamp for engaging the inner or binder edge of a sheet.

2. A music leaf turner having in combination with a suitable desk a spring actuated rocker spindle carrying a radial turning arm, the lower extremity of said spindle being extended to form a lateral operating arm, a movable trigger for normally holding

10 the operating arm in opposition to the ten-

sion of the spindle actuating spring, said trigger comprising a flat spring secured to the face of the desk and provided with a laterally deflected terminal having an eye for engagement by the extremity of the operating arm. 15

In testimony whereof he affixes his signature.

PETER H. SAN SOUCI.
